FOREIGN PATENT DOCUMENTS

WO 2012/170928 A1 12/2012

Primary Examiner — Rashida C. Walshon(74) *Attorney, Agent, or Firm* — Merchant & Gould P.C.(57) **CLAIM**

The ornamental design for a footwear, as shown and described.

DESCRIPTION

FIG. 1 is a front, top and right side perspective view of an embodiment of a footwear according to the new design; FIG. 2 is a back, bottom and left side perspective view thereof;

FIG. 3 is a right side elevation view thereof;

FIG. 4 is a left side elevation view thereof;

FIG. 5 is a front side elevation view thereof;

FIG. 6 is a back side elevation view thereof;

FIG. 7 is a top plan view thereof; and,

FIG. 8 is a bottom plan view thereof.

The broken lines in the drawings show portions that form no part of the claimed design.

The shaded areas in the drawings show a distinct portion of the claimed design and does not claim differences in texture between the various regions of the claimed design.
